CLAIM

The ornamental design for a set of transparent bands for portable digital assistant as shown and described.

DESCRIPTION

FIG. 1 is a front view of a set of transparent bands for portable digital assistant showing my new design.

FIG. 2 is a back view of the set of transparent bands for portable digital assistant.

FIG. 3 is a top view of the set of transparent bands for portable digital assistant.

FIG. 4 is a bottom view of the set of transparent bands for portable digital assistant.

FIG. 5 is a right side view of the set of transparent bands for portable digital assistant.

FIG. 6 is a left side view of the set of transparent bands for portable digital assistant.

FIG. 7 is a perspective view of the set of transparent bands for portable digital assistant; and,

FIG. 8 is a perspective view of the set of transparent bands for portable digital assistant showing the environment of use.

The broken lines in the drawings illustrate portions of the set of transparent bands for portable digital assistant that form no part of the claimed design. The broken lines showing a portable digital assistant in FIG. 8 depicts environment and forms no part of the claimed design.
